UNITED STATES PATENT OFFICE

113,016

DESIGN FOR AN ICE CRUSHING MACHINE

Jean Otis Reinecke, Chicago, Ill., assignor to
Dazey Churn & Manufacturing Company, St.
Louis, Mo., a corporation of Missouri

Application September 10, 1938, Serial No. 79,826

Term of patent 14 years

To all whom it may concern:

Be it known that I, Jean Otis Reinecke, a citizen of the United States, residing in the city of Chicago, county of Cook, and State of Illinois, have invented a new, original, and ornamental Design for an Ice Crushing Machine, of which the following is a specification, reference being had to the accompanying drawing, forming a part thereof, in which—

Fig. 1 is a top plan view, and Figs. 2 and 3 are side views of an ice crushing machine showing my new design.

I claim:

The ornamental design for an ice crushing machine, substantially as shown.

JEAN OTIS REINECKE.
